UNITED STATES PATENT OFFICE.

PIERRE J. JARRE AND ETIENNE A. JARRE, OF PARIS, FRANCE.

APPARATUS FOR FILLING TARGET-BALLS.

SPECIFICATION forming part of Letters Patent No. 279,391, dated June 12, 1883.

Application filed December 22, 1882. (No model.) Patented in France February 28, 1882, No. 147,617; in Belgium March 3, 1882, No. 57,923, and in England March 4, 1882, No. 1,062.

To all whom it may concern:

Be it known that we, PIERRE JOSEPH JARRE and ETIENNE ALPHONSE JARRE, both of Paris, France, have invented a new and improved 5 method of inflating a target-ball and ballasting it with water and closing its mouth, of which the following is a full, clear, and exact description.

My invention relates to flying rubber target-balls; and it consists in the method of filling and closing the mouths of said balls by means of an apparatus as hereinafter more fully set forth, and pointed out in the claims.

Reference is to be had to the accompanying 15 drawings, forming a part of this specification, in which similar letters of reference indicate corresponding parts in all the figures.

Figure 1 is a longitudinal sectional elevation of the air-pump used for inflating the balls 20 and filling them partly or entirely with a liquid. Fig. 2 is a vertical sectional elevation of a tank for containing an effervescent or gaseous liquid for filling the balls. Fig. 3 is a cross-sectional elevation of one of our improved 25 rubber balls, showing it half filled with a liquid. Fig. 4 is a cross-sectional elevation of a ball, showing it entirely filled with a liquid. Fig. 5 is a cross-sectional elevation of one of our improved balls, the same containing a smaller 30 ball filled with a liquid. Fig. 6 is a cross-sectional elevation of one of our improved balls, the same containing a smaller ball filled with air, the space between the inner and outer balls being filled with a liquid. Fig. 7 is a cross-sectional elevation of one of our improved 35 balls, showing the same filled with a liquid, and tied to form a sack for containing chemicals which will produce gas when permitted to mix with the liquid. Fig. 8 is a cross-sectional elevation of the neck of one of our balls 40 before the same is compressed. Fig. 9 is a sectional plan view of the same on line $x-x$; Fig. 8. Fig. 10 is a cross-sectional elevation of the neck of one of the balls, showing the same compressed. Fig. 11 is a sectional plan view of the same on the line $y-y$, Fig. 10.

A bulb or ball, A, made of soft rubber, is provided with a neck, B, which is surrounded by a copper sleeve, C. The neck B is then 50 stretched down over the outer surface of the sleeve C, and the edge of the rubber is passed

under the bottom edge of the sleeve C, as shown in Fig. 8. To give the ball or bulb sufficient weight to permit it to be thrown, we wholly or partly fill the ball with a liquid or 55 some powdered substance, liquids being preferred. The ball may be entirely or only partly filled with water; or, if desired, a smaller ball, A', can be contained within a larger ball, A, the smaller ball being filled with water and 60 being sealed at the neck. In this case the smaller ball is filled and sealed, and then the larger ball is inflated. If desired, the inner ball can be inflated, and then the space between the inner and outer balls filled with water, as shown in Fig. 6; or the ball can be filled 65 with water, and then tied by means of a string, a, a short distance below the neck, whereby a sack or bulb, A², will be formed between the tied part of the ball and the neck, which bulb 70 A² is filled with chemicals, which, when dissolved by the water in the ball A, will produce gases which will distend and enlarge the ball. The balls ready for use contain the water and the chemicals, and when the balls are to be 75 used inflated the cord a is removed, so that the chemicals can mix with the water. The ball is closed by compressing or closing the ring C at the neck, which ring can be compressed by means of pliers or any other suitable instrument; but we prefer to use the device which will be described hereinafter. To fill the balls with air and water we use an air-pump, D, which consists of a vertical cylinder, E, provided at its bottom with an outlet-channel, F, which terminates in a curved outlet-pipe, G, the end of which is tapered and adapted to be passed into the necks of the balls A. The cylinder E contains a piston, H, which is attached to a rack, J, projecting 90 from the top of the piston and from the top of the cylinder, which rack J engages with a pinion, K, mounted on a shaft, L, having a crank-handle, M, whereby the piston will be raised or lowered by turning the crank-handle 95 M. An elbow-pipe, N, projects from the upper part of the cylinder E, and in the upper end of the said elbow-pipe N the lower end of a funnel, O is placed, by means of which funnel and elbow-pipe the requisite quantity 100 of water can be conducted into the cylinder. A nut, P, is mounted on the rack-bar J, and

can be locked on the same by means of a binding-screw, P'. The nut P is provided on its outer surface, along the outer edge, with an annular projecting flange. The rack-bar J passes 5 through a standard, Q, on the top of the cylinder, which standard is provided in its upper surface and along the outer edge with an annular flange corresponding with the surface of the nut P. If the balls are to be filled with 10 a gaseous or other effervescent liquid, the nozzle R is placed into the neck of the ball, which nozzle R is formed at the upper end of a pipe, R', which projects to the bottom of the closed vessel S, which contains the gaseous or effervescent liquid. As soon as the cock of the 15 pipe R is opened the pressure of the gas in the box S forces the gaseous liquid and some of the gas into the ball, which is thus distended and partly or wholly filled.

20 The balls are filled by means of the air-pump, as follows: The piston is raised and the water is poured through the funnel O and elbow-pipe N into the bottom of the cylinder, and the end of the curved tube G is passed into the neck 25 of the ball. If the piston is forced downward by turning the crank-handle M, the air in the cylinder below the piston is compressed and forces the water through the channel F and the tube G into the ball A, and then the compressed air is also forced into the ball, whereby the same will be distended and enlarged to the desired size. If the nut P is held at the 30 top of the rack-bar J, the piston can be lowered to the bottom of the cylinder, and all the compressed air will be forced into the rubber ball, which will be enlarged considerably. If it is desired that the ball shall not be so large, the nut P is adjusted a greater or less distance from the upper end of the rack-bar J, so that 35 the said rack-bar and the piston H, attached to the same, cannot be lowered the full length of the rack-bar, as the nut P strikes against the upper end of the standard Q before the piston has reached the bottom of the cylinder.

40 45 The quantity of water in each ball can be varied, and, as previously stated, the water

can be held in various manners. After the ball has been filled and inflated it is disconnected from the end of the tube G, and at the same time the sleeve B is pressed together by 50 the fingers, so as to retain the air within the ball. The neck is again seized a short distance behind the sleeve C, and the neck is placed between the nut P and the top of the standard Q, and by turning the crank-handle 55 M the nut P is suddenly moved down upon the upper end of the standard Q, and thereby the flanges of the nut P and the standard Q will indent the flattened sleeve at the middle, and thereby press the rubber within the sleeve 60 so tightly together that a perfectly close and air-tight joint is formed.

Having thus described our invention, what we claim as new, and desire to secure by Letters Patent, is—

1. The apparatus for filling target-balls with water and air herein described, consisting of a piston forcing water and air into a ball, and clamping means, substantially as described, supported, respectively, upon the piston-rod 70 and cylinder, between which the ball shall be clamped and hermetically sealed, as set forth.
2. In an apparatus for filling target-balls with water and air and hermetically closing 75 the mouths of the same, the combination of the cylinder E and piston-rod H J with the standard I, secured to the upper part of the cylinder, and having an annular flange at its upper end, and the nut P, secured near the upper end of the piston-rod, between which nut and flange the balls may be clamped and hermetically sealed after being filled with air and water through the operation of the piston mechanism, substantially as described, and for 80 85 the purpose set forth.
